(57) **CLAIM**

The ornamental design for a tape cartridge, as shown and described.

DESCRIPTION

FIG. 1 is a perspective view of a tape cartridge showing our new design;

FIG. 2 is a front view thereof;

FIG. 3 is a rear view thereof;

FIG. 4 is a top view thereof;

FIG. 5 is a right side view thereof;

FIG. 6 is a left side view thereof;

FIG. 7 is a bottom view thereof;

FIG. 8 is a cross section taken along line 8—8 of FIG. 4; FIG. 9 is a cross section taken along line 9—9 of FIG. 4; and,

FIG. 10 is a cross section taken along line 10—10 of FIG. 7.

The broken lines are for illustrative purpose only and form no part of the claimed design.
